Filed Dec. 31, 1959, Ser. No. 863,168
2 Claims. (Cl. 200—80)

This invention relates to fluid flow-responsive switch devices, and more particularly to a switch device which may be employed to modulate the flow of materials through a processing system in accordance with the flow of air past a control point in the system, the device being arranged to operate automatically to provide a control action responsive to the failure of air flow at the control point.

A main object of the invention is to provide a novel and improved fluid flow-responsive switch device which is simple in construction, which is easy to install, and which is reliable in operation.

A further object of the invention is to provide an improved fluid flow-responsive switch device especially adapted for use in modulating the flow of dry material through a pneumatic conveying system in accordance with the flow of air past a control point in the system, the device involving relatively inexpensive components, being durable in construction, and being sensitive in its response.

Further objects and advantages of the invention will become apparent from the following description and claims, and from the accompanying drawings, wherein:

FIGURE 1 is a vertical cross sectional view taken through an improved fluid flow-responsive switch device according to the present invention.

FIGURE 2 is a horizontal cross sectional view taken substantially on the line 2—2 of FIGURE 1.

FIGURE 3 is a fragmentary horizontal cross sectional view taken substantially on the line 3—3 of FIGURE 1.

Referring to the drawings, 11 generally designates an improved fluid flow-responsive switch device according to the present invention. The device 11 comprises a housing 12 adapted to be mounted in a fluid flow conduit, for example, in an air conduit of a pneumatic conveying system, or similar processing plant. The housing 12 is generally circular in shape and is provided with an inlet opening 13 in the side walls thereof, whereby fluid may enter the housing. If desired, an intake duct 14 may be secured to the side wall of the housing to guide air or similar fluid into the housing at the intake opening 13 thereof, although under certain conditions, the duct 14 is not required. The bottom wall 15 of housing 12 is provided with a central discharge passage 16 which allows the fluid to leave the housing.

Designated at 18 is a squared vertical shaft which extends axially into the housing 12 and which extends upwardly through a generally cylindrical auxiliary housing 19 secured axially to the top wall of the main housing 12. The auxiliary housing 19 may comprise the mating upper and lower segments 20 and 21, said segments being formed with abutting connecting flanges 22 and 23 which are fastened together by suitable bolts 24 extending through the flanges 22 and 23 and spaced at uniform distances around said flanges. A sealing gasket 25 is preferably interposed between the connecting flanges 22 and 23. The bottom segment 21 of the auxiliary housing 19 is secured by fastening screws 26 to the thickened rim 27 formed on the top wall of main housing 12 around the central aperture 28 thereof through which the shaft 18 extends.

The bottom wall 29 of housing segment 21 is formed with a central circular opening 30 which rotatably receives the squared vertical shaft 18. Shaft 18 is formed with a reduced cylindrical top end portion 31 which is

2

journaled in a bearing bushing 32 secured in an upstanding axial conduit 33 formed centrally in the top wall 34 of upper housing segment 19. Secured to the lower portion of the squared shaft 18 is a bearing collar member

5 35 which is rotatably supported on a bearing washer 36 surrounding the shaft 18 and resting on the bottom wall 29 of lower housing segment 21. Collar 35 is integrally formed with a cylindrical upstanding guide sleeve 37 in which is positioned a coiled spring 38 which exerts upward biasing force on a squared sleeve member 39 slidably and non-rotatably engaged on the upper portion of the squared shaft 18. The lower end of the spring 38 is supported on the collar member 35.

Secured to the bottom end of the squared shaft 18 is 15 an impeller assembly 40 comprising a circular top supporting disc 41 and an annular bottom ring element 42 disposed parallel to the top disc 41. A plurality of arcuately curved vertical vane elements 43 connect the top disc 41 to the annular bottom ring element 42, the 20 arcuate vane elements 43 serving to receive the flowing fluid in the air conduit in which the device is mounted, causing the impeller 40 to rotate in response to the movement of the flowing fluid, the fluid discharging through the bottom passage 16 of housing 12. The fluid enters the 25 housing through the intake opening 13, being guided thereto by the intake duct 14 when such duct is employed with the housing.

Designated at 44 is a switch arm which is hinged at 45 to an inwardly projecting horizontal lug 46 formed in 30 the top housing segment 19, the arm 44 being provided with an opening 46 through which the shaft member 18 extends and in which said shaft member is freely rotatable. Arm 44 is provided at its free end with a depending, transversely extending contact element 47 which is located 35 immediately above a pair of spaced switch contacts 48, 48 mounted on an insulating support 49 secured to the wall of upper housing segment 19. The bridging switch conductor 47 may be fastened in any suitable manner to the switch arm 44, and may be suitably insulated therefrom. As will be apparent from FIGURE 1, when the switch arm 44 is allowed to rotate downwardly, namely, in a counterclockwise direction, as viewed in FIGURE 1, the conductive bridging member 47 moves into engagement with the spaced switch contact elements 48, 48, 40 thereby closing the switch. A biasing spring 50 is provided between the switch arm 44 and the top wall 34 of upper housing segment 20, the spring 50 receiving an upstanding guide lug 51 in its lower end portion, said guide lug being formed integrally on the switch arm 44 and receiving a depending guide lug 52 at its top end, said 45 guide lug 52 being integrally formed in top wall 34 of upper housing segment 20. The switch arm 44 is normally supported by the circular top flange 53 formed on the top end of the sleeve member 39, a bearing washer 54 being interposed between flange 53 and arm 44, as is clearly shown in FIGURE 1, to transmit the upward biasing force of the coiled spring 38 from flange 53 to said switch arm 44. Spring 38 is of sufficient strength to overcome the downward biasing force exerted by the coiled 50 spring 50 on the arm 44 under normal conditions, namely, when the shaft 18 is stationary or is rotating at a speed less than a predetermined definite value, as will be presently explained.

Designated at 60 are a plurality of weight members of 55 any suitable heavy material, such as lead, or the like, said weight members being spaced around the upstanding guide sleeve 37 and being connected between flange 53 and flange 35 by flexible link means which allows the weight member 60 to move outwardly by centrifugal force. Thus, each weight member 60 is provided with a bottom lug 61 to which is pivotally connected the top 60 end of a bottom connecting link 62, the bottom end of the

link being pivotally connected to a radial flange 63 integrally formed with the bottom flange 35 and the spring guide sleeve 37, as is clearly shown in FIGURE 1. The top end of each weight member 60 is formed with a lug 64 to which is pivotally connected the bottom end of a top connecting link 65. The top end of each link 65 is formed with a swivel ball 66 which is rotatably received in a suitable swivel socket 67 formed in the flange 53, as shown. Thus, the link rod 65 extends through an aperture in the flange 53, and the generally spherical socket 67 is formed around the aperture to receive the enlarged generally spherical swivel ball 66 of the link member 65.

As shown in FIGURE 3, four weight members 60 may be provided, although any desirable number of such weight members may be employed.

In operation, when the shaft 18 rotates at more than a specific predetermined speed, due to the rotation of the impeller assembly 40 produced by flow of air through the housing 12, the weight members 60 move outwardly sufficiently to cause the bridging conductor 47 to engage the switch contact elements 48, 48. This closes the switch, whereby to cause material to be fed to the system, or to provide any other desired control action required to be performed in the system simultaneously with the movements of the air through the duct or other passage in which the device is mounted. When the flow of air drops below the required speed, whereby insufficient air is moving through the passage in which the device is mounted, the impeller 40 slows down, allowing the weights 60 to move inwardly toward their normal positions, whereby the spring 38 elevates the switch arm 44 and causes conductor 47 to disengage from the switch contacts 48, 48, opening the switch. This may stop the feeding of materials into the system until an adequate flow of air is restored in the passage in which the device is mounted.

A conduit 70 is formed integrally with the upstanding axial conduit 33 and is integrally connected with the top wall 34 of upper housing segment 20, providing a passage for electrical conductors associated with the switch device. Thus, respective conductors 71 and 72 may be connected to the switch contact elements 48, 48, said conductors extending upwardly through the conduit 70 and the axial upstanding conduit 33 to the motor or other device being controlled.

Rigidly secured on the intermediate portion of the lower housing segment 21 is a flange 72 provided with a plurality of radial sleeve elements 73 in which are slidably mounted radially extending, horizontal supporting rods 74 which may be employed to support the device on the top wall of an air duct or similar passage with the main housing 12 positioned inside the duct or similar passage and disposed in a position to respond to the variations in the flow of air through said duct or passage. The rod members 74 are slideable outwardly to engage the marginal portions of an opening in the top wall of the duct or passage so as to support the device in its operating position.

The flange 72 may be secured on the lower housing segment 21 at any desired position thereon, said flange being provided with a clamping band 76 which is split and provided with respective opposing lug elements 77 and 78 through which extends a clamping bolt 79, so that the band 76 may be rigidly secured in an adjusted position on the lower housing segment 21 by tightening the clamping bolt 79.

Obviously, if so desired, the band 76 may be engaged on the upper housing segment 20 if it is necessary that the main housing 12 be supported in a lower position in the duct or passage on which the device is mounted.

While a specific embodiment of an improved fluid flow-responsive switch device has been disclosed in the foregoing description, it will be understood that various modifications within the spirit of the invention may occur to

those skilled in the art. Therefore, it is intended that no limitations be placed on the invention except as defined by the scope of the appended claims.

What is claimed is:

5 1. A fluid flow-responsive switch device comprising a generally circular housing adapted to be mounted vertically in a fluid flow conduit, said housing having a peripheral fluid inlet opening and a central bottom fluid discharge opening, a vertical squared shaft member journaled in said housing, a vane assembly secured to the lower end of said shaft member and being disposed in the fluid flow path between said inlet opening and said discharge opening, whereby to rotate said shaft member responsive to fluid flow, a squared sleeve member slidably and non-rotatably engaged on said shaft member, collar means secured to said shaft member and spaced from said sleeve member, outwardly movable vertically elongated weight members normally disposed externally adjacent to and parallel to said shaft member, link means 10 connecting the opposite ends of said weight members respectively to said sleeve member and said collar means, a switch arm pivoted in said housing above and adjacent to said sleeve member, a contact member mounted in the housing subjacent said switch arm and being engageable by said switch arm, first spring means biasing said switch arm downwardly toward engagement with said contact member, and second spring means biasing said sleeve member upwardly into engagement with said switch arm and opposing said first spring means, said weight members being movable outwardly by centrifugal force to overcome the force of said second spring means responsive to rotation of said shaft member above a predetermined speed.

2. A fluid flow-responsive switch device comprising a generally circular housing, a flange secured to said housing and extending outwardly therefrom, a plurality of spaced radial sleeve elements on said flange, radially extending supporting rods slidably mounted in said radial sleeve elements, for supporting said housing in a fluid flow conduit, the lower portion of said housing having a peripheral fluid inlet opening and a central bottom fluid discharge opening, a vertical square shaft member journaled in said housing, a vane assembly secured to the lower end of said shaft member and being disposed in the fluid flow path between said inlet opening and said discharge opening, whereby to rotate said shaft member responsive to fluid flow, a squared sleeve member slidably and non-rotatably engaged on said shaft member, collar means secured to said shaft member and spaced from said sleeve member, outwardly movable vertically elongated weight members normally disposed adjacent to and parallel to said shaft member, link means connecting the opposite ends of said weight members respectively to said sleeve member and said collar means, a switch arm pivoted in said housing above and adjacent to said sleeve member, a contact member mounted in the housing subjacent said switch arm and being engageable by said switch arm, first spring means biasing said switch arm downwardly toward engagement with said contact member, and second spring means biasing said sleeve member upwardly into engagement with said switch arm and opposing said first spring means, said weight members being movable outwardly by centrifugal force to overcome the force of said second spring means responsive to rotation of said shaft member above a predetermined speed.
